UNITED STATES PATENT OFFICE.

FRIEDRICH GREINER, OF CANNSTATT-STUTTGART, GERMANY.

COOLING DEVICE.

Application filed August 25, 1924. Serial No. 734,146.

To all whom it may concern:

Be it known that I, FRIEDRICH GREINER, a citizen of the German Republic, residing at Cannstatt-Stuttgart, Germany, Teckstrasse 35, have invented certain new and useful Improvements in Cooling Devices, of which the following is a specification.

This invention relates to devices for improving the cooling action in cast machine parts, particularly in such parts as cylinders 10 of internal combustion engines.

For the purpose of ensuring a solid or dense casting, for instance in the case of engine cylinders, it is known to embed 15 pieces of sheet metal or the like into the castings when casting them. However it has always been usual to allow these cast in pieces to extend at the most to the surface of the casting, but not beyond it.

Further it is known to cool cylinders of 20 internal combustion engines by means of ribs constituted by pieces of sheet metal cast into the cylinder bodies at their circumference.

It has now been found that it is desirable 25 to utilize the sheet metal pieces which have hitherto been used for ensuring density of casting, for an additional purpose, namely improving the dissipation of heat. This 30 is effected by departing from the procedure previously employed and allowing the sheet metal pieces to project beyond the cross-section of the casting in the form of ribs or the like. Such sheet metal pieces are 35 preferably cast in at the points where the cross-sections of the material are such that, during the cooling of the casting in the mould, they can only give off their heat to the exterior slowly, that is to say they re-

main liquid for a longer time than is desirable and consequently, for well known 40 reasons, frequently show formation of pipes. It is also precisely at these places that heat accumulates during the operation 45 of the engine or other machine, and the prolongation of the cast-in pieces of sheet metal or the like, affords a suitable means for carrying away the heat which would otherwise accumulate.

In the case of cylinders of internal combustion engines, the cast-in pieces can be allowed to project into the hollow space of 50 the cooling jacket, and by suitably bending the projecting portions, the heat-exchange surface can be increased to any desired extent.

Two constructions embodying the device according to the present invention are illustrated by way of example in the accompanying drawing. Figure 1 represents a section 60 through the cylinder axis of one half of a four-cylinder block. Figure 2 is a section on the line 2—2 of Figure 1. Figure 3 is a section on the line 3—3 of Figure 2. Figure 4 is a section at right angles to the 65 axis of a cylinder cover intended for example for crude oil engines.

Referring to Figures 1 to 3, in the middle between each two adjoining cylinders *a* and two adjoining valve chambers *b*, the 70 pieces *c* or *d* made of sheet iron are cast in during the casting of the cylinder block. During the casting operation they take up, at the places which otherwise cool slowly, those quantities of heat which otherwise 75 would maintain the cast iron liquid for too long a period at the places in question, and partly owing to the said action, and partly owing to their own physical and chemical properties, they lead to the production 80 in a reliable manner of a dense or compact casting. In accordance with the invention these cast-in pieces project beyond the cross section of the casting in the form of ribs, preferably into the 85 cooling chamber or into the chambers *e* traversed by the cooling water, so that during the working of the engine, they serve to carry away heat from those places where otherwise there would be insufficient provision for the elimination of heat.

Reference to Figure 3 shows how the cast-in intermediate sheets or plates allow each 90 conduit *e* of the cooling jacket to be favourably utilized.

In the case of the cylinder cover of the cross section shown in Figure 4, the cast-in plates which carry away the heat are marked *f*.

There are of course numerous other methods of utilizing the device according to the present invention in addition to those indicated by the examples previously mentioned. The cast-in pieces could of course be allowed to project beyond the surface of the casting, 100 and be utilized also for air cooling or other kinds of cooling. By suitably bending, corrugating, rolling up and the like, the projecting portions, their heat-carrying away surface could be increased to any desired 105 extent; further they could themselves be formed into conduits or tubes for the pass-

age of a cooling medium, or conversely, tubes or the like traversed by a cooling medium could be cast in or cast on the casting, if necessary by means of projecting ribs, 5 lugs or the like.

The invention is applicable not only to internal combustion engines, but to all such apparatus where similar problems of carrying away heat arise.

10 What I claim and desire to secure by Letters Patent of the United States is:—

1. In a cast metal article, cooling ribs therefor consisting of the projecting portions of chill plates imbedded in the article 15 at the casting thereof.

2. In a cast metal article, a chill plate imbedded in the article at the casting thereof, said plate projecting beyond the surface of the article for forming a cooling rib therefor.

3. In an internal combustion engine cylinder casting including a cooling jacket, cooling ribs for said casting formed by the extended portions of chill plates retained therein, said extended portions projecting 20 within said cooling jacket.

FRIEDRICH GREINER.
